ABSTRACT

A liner machine for applying a sealing compound to a can end or lid. The liner machine includes a motor drive dual turret system. The turret system is installed at the top of a table or platform surface and two turrets rotate in opposition directions from one another, simultaneously or independently at same or different times. Each turret includes a plurality of workstations which extend out from each turret facing away from each other. The workstations receive an individual lid, which is delivered via a starwheel from a downstacker to each turret system. Each rotates in a direction that is opposite the direction that its respective turret system rotates, and in a direction that is opposite the direction that the other starwheel rotates. Sealant injectors in the turret systems apply sealant to each lid as the lids rotate around each turret system.

LINER MACHINE FOR APPLYING SEALING COMPOUND

CROSS-REFERENCE TO RELATED APPLICATION

This application is a U.S. Non-Provisional Application claiming the benefit of and priority to U.S. patent application Ser. No. 17/535,882, filed Nov. 26, 2021, entitled LINER MACHINE FOR APPLYING SEALING COMPOUND, which claims the benefit of and priority to U.S. Provisional Application No. 63/148,063, filed Feb. 10, 2021, entitled LINER MACHINE FOR APPLYING SEALING COMPOUND, and U.S. Provisional Application No. 63/118,851, filed Nov. 27, 2020, entitled LINER MACHINE FOR APPLYING SEALING COMPOUND, the disclosures of which are incorporated herein by reference in their entirety.

FIELD OF TECHNOLOGY

The present disclosure relates generally to a liner machine for applying a sealing compound to an article, and more particularly, to such a machine for applying a sealing compound to a can end.

BACKGROUND

Compound end liner machines are used in can production systems. In some examples, liner machines are engineered to run beer and beverage ends, sanitary ends, and twist-off closures. Liner machines apply sealant to the underside of a can end to facilitate sealing attachment of the can end to a can container. When the can end is attached to the upper flange of the can, the applied sealant seals the can rim and the can end to close and seal the can.

Liner machines may include a turret which rotates on a vertical spindle and has a number of workstations spaced around the spindle. Each workstation may each be adapted to support a can end. Mounted at each workstation may be an injector nozzle of an applicator (or sealant dispensing gun) connected to a supply manifold fixed to the top of the turret. A supply source provides sealing compound to the supply manifold, which then feeds the sealing compound to the applicator. The injector nozzle applies the sealing compound to a can end. Liner machines may be equipped with applicators for applying water-base, solvent-base, or plastic sol compounds, by way of example.

A can end is generally supported by a chuck member, driven by a chuck drive, which locates the can end adjacent the applicator in the desired position. The can end is then rotated at a high speed by the chuck member while the applicator or sealant dispensing gun valve is opened, thus resulting in an accurate, even application of liquid sealant onto the underside of the can end. After application, the liquid sealant cures to form a solidified ring of resilient sealing material.

Can ends may be fed into each workstation on one side of a turret and discharge at an exit chute located approximately 180° from the feed position. After a workstation passes the exit chute, a mechanical brush mechanism wipes against the injector nozzle in an attempt to clean any excess sealing compound from the surface of the injector nozzle. In some cases, the brush mechanism fails to adequately clean the injector nozzle. The injector nozzle may become dirty and gummed up, and as a result, require frequent replacement, thereby causing substantial downtime for the liner machine.

Finally, at least some compound end liner machines may be large, bulky machines that are difficult to maintain. For example, at least some compound end liner machines may include a table or platform surface and the rest of the equipment may be positioned in the middle of the table or platform surface. The table or platform surface may be large to accommodate the size of the axillary systems and the drive system such that the equipment on the table or platform surface is difficult to access for maintenance.

SUMMARY

The described technology includes methods, systems, devices, and apparatuses that support liner machines for applying a sealing compound to an article. Generally, the described technology provides for high performance, scalable turret liner machines for applying sealing compound to can ends, where the turrets and their respective starwheels move in synchronized timing, each turret moving in opposite directions from each other, in opposite directions from their respective starwheel.

In some implementations, the disclosed liner machines require components specifically manufactured for the direction of rotation of each component part. For example, some of the components in a first turret system may require left-handed threads, whereas the complementary components in a second turret system rotating in the opposition direction may require right-handed threads. Other customized components are contemplated as each turret system in the liner machine mirrors the other turret system.

In some implementations, a synchronized turret system includes a first turret and its respective starwheel operating simultaneously with the second turret and its respective starwheel. In other implementations, independent turret systems are configured where the first turret and its respective starwheel operate independently from the second turret. For example, the first turret and its respective starwheel may be operating while the second turret and its respective starwheel do not operate. This independent operation allows for access, downtime, and maintenance to one of the turrets and its respective system. In another example, the first turret and its respective starwheel may be operating while the second turret and its respective starwheel operate, yet each turret has the capability of operating or not operating when the other turret is operating.

In some implementations, the disclosed technology includes a sealant liner apparatus which has two motor driven turret systems, each turret system driven in a direction that is opposite the direction that the other turret system is driven. Each turret system may have a plurality of workstations spaced apart, extending outwardly from a circumference thereof, and adapted for receiving an individual can end, at least one sealant applicator electronically controlled to apply a sealant on at least one individual can end, and two belt or gear driven downstackers, each downstacker including a respective starwheel, and each starwheel driven in a direction opposite to the direction that its respective turret system is driven. The first starwheel may rotate in a direction opposite to the second starwheel.

In some implementations, the downstackers are positioned in the corners of the liner machine system on the same side of the system as the exit chutes. For example, each downstacker may be located approximately ±45° from a center axis of each starwheel. Compared to that, in other liner machine systems, can ends may be fed from a downstacker into each workstation on one side of a turret and discharge at an exit chute located approximately 180° from

the feed position (in other words, on the opposite side of the liner machine system). The positioning of the downstackers in the disclosed liner machine systems facilitates more travel distance for the can end from where it is fed to where it is discharged, thereby increasing the lining time of an individual can end.

In some implementations, the sealant liner apparatus includes at least one chuck member to support an individual can end and rotate the individual can end for sealing compound application. In some implementations, the sealant liner apparatus also includes two lower chuck drives, each lower chuck drive configured to each rotate in a direction opposite the other lower chuck drive.

This Summary is provided to introduce a selection of concepts in a simplified form that are further described below in the Detailed Description. This Summary is not intended to identify key features or essential features of the claimed subject matter, nor is it intended to be used to limit the scope of the claimed subject matter. Other features, details, utilities, and advantages of the claimed subject matter will be apparent from the following more particular written Detailed Description of various implementations as further illustrated in the accompanying drawings and defined in the appended claims.

These and various other features and advantages will be apparent from a reading of the following Detailed Description.

BRIEF DESCRIPTION OF THE DRAWINGS

FIG. 1 illustrates an example of a turret liner machine system in accordance with aspects of the present disclosure.

FIG. 21 illustrates an example of a turret liner machine system in accordance with aspects of the present disclosure.

FIG. 22 illustrates an example of a turret liner machine system in accordance with aspects of the present disclosure.

FIG. 23 is a flowchart of operations that support a dual 10 turret liner machine system in accordance with aspects of the present disclosure.

DETAILED DESCRIPTION

15 In the following description, for the purposes of explanation, numerous specific details are set forth in order to provide a thorough understanding of the present invention. It will be apparent, however, to one skilled in the art that the present invention may be practiced without some of these 20 specific details. For example, while various features are ascribed to particular implementations, it should be appreciated that the features described with respect to one implementation may be incorporated with some implementations as well. Similarly, however, no single feature or features of 25 any described implementation should be considered essential to the invention, as some implementations of the invention may omit such features.

The disclosed technology includes methods, systems, devices, and apparatuses that support liner machines for 30 applying a sealing compound to an article. Generally, the described technology provides for turret liner machines for applying sealing compound to a container closure member or can end, where the turrets and their respective starwheels move in synchronized timing, the turrets moving in opposite 35 directions from each other and in opposite directions from their respective starwheels, or to move independently, where each turret can move while the other turret is moving or not moving.

Each turret may be connected to a downstacker, which is 40 a feed unit that separates and feeds the can ends or lids (e.g., aluminum can lids) to each turret. In some implementations, the disclosed technology includes a dual turret liner machine for applying a sealing compound to an article, and more particularly, for applying a sealing compound to a can end or lid. The dual turret liner machine applies a sealant to metal lids, each metal lid being received from a supply conveyor and discharged to a discharge conveyor via an exit chute. In some implementations, the dual turret liner machine includes two turret systems driven by a single main 50 drive motor. In some implementations, the liner machine technology may incorporate any number of turrets, drives, motors, chucks, chuck drives, downstackers, and starwheels. The disclosed technology is aimed at performing high speed and high-volume end production with scalable systems.

55 The turret systems may be referred to herein as the system including a turret, a plurality of workstations, and applicators with nozzles for sealant application. Each turret system may be adapted to receive lids from a starwheel which is adapted to receive the lids from a downstacker. The turret systems may be installed at the top of a table or platform surface and rotate in opposition directions from one another. The turret systems each include a plurality of workstations which extend out from each turret facing away from each other.

60 Specifically, each individual workstation receives an individual lid from a downstacker. In the dual turret system, the liner machine includes two downstackers, each downstacker

connected to each turret system. A starwheel adapted to deliver lids from the downstacker to the turret is rotatable in an opposite direction from its respective turret, and in an opposite direction from the other starwheel. Sealant injectors or applications may be installed in the workstations to apply sealant to each metal lid as the lids rotate around each turret.

When applying sealant to a can end or container closure member, it may be desirable to closely control the lining time of the can ends. It may be beneficial to maximize the application time of sealant on can ends in order to ensure comprehensive coverage. In the disclosed technology, the downstackers are located at the outer corner edges of the liner machine system, at approximately $\pm 45^\circ$ from the center axis of the turret (as shown in FIG. 2, depicted with the arrows and axis line), rather than directly opposite the exit chutes to allow for additional lining time of the can ends.

When a lid or can end leaves a starwheel, the can end is in a down position. The starwheel rotates the lid around to meet a lower chuck. The lower chuck picks up the lid, and the lift cam lifts the lower chuck to a workstation on the turret system. When the lift cam is in the up position, rising above the platform to the applicator, the lid is rotated approximately 150° in the upright position, as the sealant is applied to the lid. In the disclosed technology, as a result of the locations of each downstacker, each lift cam is elongated. The longer length of the lift cam allows for the lid or can end to be on the lift cam longer, thus, allowing for more sealant application time. In other liner machine technology, lift cams are approximately 125° in duration (of a 360° rotation) in the upright position (not accounting for the up ramp and down ramp distance). In the disclosed technology, the lift cams are approximately 150° degrees because of the distance from a downstacker to the exit chute.

As a result of the configurations, and shared components and processes included in the disclosed systems, there are lower labor costs (more EPM results in less staffing), smaller machine footprints (e.g., an example machine may be 18 sq ft running 5500 epm compared to 19 sq ft running at 2500 epm, less machines requiring less user aisle space), lower power costs (less energy required), increased lining time, easier maintenance, and a single compound supply for the certain systems (e.g., 5550 epm requires only one compound drop).

Aspects of the disclosure are further illustrated by and described with reference to apparatus diagrams, system diagrams, and flowcharts that relate to liner machines for applying a sealing compound to an article.

This description provides examples, and is not intended to limit the scope, applicability or configuration of the principles described herein. Rather, the ensuing description will provide those skilled in the art with an enabling description for implementing various aspects of the principles described herein. As can be understood by one skilled in the art, various changes may be made in the function and arrangement of elements without departing from the application.

FIG. 1 illustrates an example of a turret liner machine system 100 in accordance with aspects of the present disclosure. Specifically, FIG. 1 is a perspective view of a synchronized dual turret liner machine system 100 for applying a sealing compound to a can end or lid 490 (shown in FIG. 4). The synchronized dual turret liner machine 100 applies a sealant (not shown) to metal lids, each metal lid being received from a supply conveyor (not shown) and discharged to a discharge conveyor (not shown) via an exit chute (see, e.g., exit chute 212a and 212b in FIG. 2). In the illustrated embodiment, the dual turret liner machine 100

includes two turret systems 102a and 102b driven by a single main drive motor 140. The main drive motor 140 located proximate to the first turret system may be configured to operate in conjunction with the main drive driven gear located proximate to the second turret system. In some implementations, the liner machine technology may incorporate any number of turrets, drives, motors, chucks, chuck drives, downstackers, and starwheels. The disclosed technology is aimed at performing high speed and high-volume end production with scalable systems.

The turret systems 102a and 102b may be referred to herein as systems including turrets 106a and 106b, a plurality of workstations 116, and applicators 114 with nozzles 122 for sealant application. Each turret system may be adapted to receive lids from a starwheel (see, e.g., starwheels 520a and 520b in FIG. 5) which is adapted to receive the lids from a downstacker (e.g., downstackers 104a and 104b). The turret systems 102a and 102b may be installed at the top of a table or platform surface 118 and rotate in opposition directions from one another (as depicted by the arrows). The turret systems 102a and 102b each include a plurality of workstations 116 which extend out from each turret system facing away from each other.

The workstations 116 receive an individual lid from a downstacker. In the dual turret system 100, there are two downstackers 104a and 104b, each downstacker connected to each turret system 102a and 102b. The starwheels 520a and 520b adapted to deliver lids from each downstacker to each turret are rotatable in an opposite direction from its respective turret, and in an opposite direction from the other starwheel 520b or 520a. Sealant injectors or applications 114 may be installed in the workstations to apply sealant to each metal lid as the lids rotate around each turret 106a and 106b.

As shown in FIG. 1, a rod cage (e.g., rod cage 110a or 110b) is attached to each downstacker 104a and 104b. In some implementations, rod cages 110a and 110b may not be used and a belt (not shown) or conveyor (not shown) feeds can ends directly into the machine.

When applying sealant to a can end or container closure member, it may be desirable to closely control the lining time of the can ends. It may be beneficial to maximize the application time of sealant on can ends in order to ensure comprehensive coverage. In the disclosed technology, the downstackers are located at the outer corner edges of the liner machine system, at approximately $\pm 45^\circ$ from the center axis of the turrets 106a and 106b (as shown in more detail in FIG. 2, depicted with the arrows and axis line), rather than directly opposite the exit chutes (see, e.g., exit chutes 212a and 212b in FIG. 2) on the other side of the table or platform, to allow for additional lining time of the can ends.

As shown in FIG. 1, the turret liner machine system 100 includes two turret systems 102a and 102b operating in a single machine. The two turret systems 102a and 102b share a plurality of auxiliary systems that enable the turret liner machine system 100 to reduce complexity, reduce auxiliary systems, and reduce the overall footprint of the turret liner machine system 100. For example, the turret liner machine system 100 may include an electrical system (not shown), a compressed air system (not shown), an air cooler (not shown), an oil cooling system (not shown) including an oil cavity (not shown), and a feed of sealant (not shown). The arrangement of two turret systems 102a and 102b operating in a single machine enables the two turret systems 102a and 102b to share the auxiliary systems, reducing complexity, reducing auxiliary systems, and reducing the overall footprint of the turret liner machine system 100.

FIG. 2 illustrates an example of a turret liner machine system 200 in accordance with aspects of the present disclosure. Specifically, FIG. 2 is a top view of a synchronized dual turret liner machine system 200 for applying a sealing compound to a can end or lid 490 (shown in FIG. 4). The dual turret liner machine 200 applies a sealant to metal lids, each metal lid being received from a supply conveyor (not shown) and discharged to a discharge conveyor (not shown) via an exit chute e.g., exit chutes 212a and 212b. The dual turret liner machine 200 includes two turret systems 202a and 202b driven by a single main drive motor (see, e.g., main drive motor 140 in FIG. 1). In some implementations, the liner machine technology may incorporate any number of turrets, drives, motors, chucks, chuck drives, downstackers, and starwheels. The disclosed technology is aimed at performing high speed and high-volume end production with scalable systems.

The turret systems 202a and 202b may be referred to herein as systems including turrets 206a and 206b, a plurality of workstations 216, and applicators 214 with nozzles (see, e.g., nozzles 122 in FIG. 1) for sealant application. Each turret system 202a and 202b may be adapted to receive lids from a starwheel (see, e.g., starwheels 520a and 520b in FIG. 5) which is adapted to receive the lids from a downstacker 204a and 204b. The turret systems 202a and 202b may be installed at the top of a table or platform surface 218 and rotate in opposition directions from one another (as depicted by the arrows). The turret systems 202a and 202b each include a plurality of workstations 216 which extend out from each turret system facing away from each other.

The workstations 216 receive an individual lid (not shown) from a downstacker. In the dual turret system 200, there are two downstackers 204a and 204b, each downstacker 204a and 204b connected to each turret system 202a and 202b. The starwheels 520a and 520b adapted to deliver lids from each downstacker to each turret 206a and 206b are rotatable in an opposite direction from its respective turret 206a and 206b, and in an opposite direction from the other starwheel 520b or 520a. Sealant injectors or applications 214 may be installed in the workstations 216 to apply sealant to each metal lid as the lids rotate around each turret.

When applying sealant to a can end or container closure member, it may be desirable to closely control the lining time of the can ends. It may be beneficial to maximize the application time of sealant on can ends in order to ensure comprehensive coverage. In the disclosed technology, the downstackers 204a and 204b are located at the outer corner edges of the liner machine system, at approximately $\pm 45^\circ$ from the center axis of the turret (as depicted with the arrows and axis line), rather than directly opposite the exit chutes 212a and 212b on the other side of the table or platform, to allow for additional lining time of the can ends.

FIG. 3 illustrates an example of a turret liner machine system 300 in accordance with aspects of the present disclosure. Specifically, FIG. 3 is a side view of a synchronized dual turret liner machine system 300 for applying a sealing compound to a can end or lid 490 (shown in FIG. 4). The dual turret liner machine 300 applies a sealant to metal lids, each metal lid being received from a supply conveyor (not shown) and discharged to a discharge conveyor (not shown) via an exit chute (see, e.g., exit chute 212a and 212b in FIG. 2). The dual turret liner machine 300 includes two turret systems 302a and 302b driven by a single main drive motor 340. In some implementations, the liner machine technology may incorporate any number of turrets, drives, motors, chucks, chuck drives, downstackers, and starwheels. The

disclosed technology is aimed at performing high speed and high-volume end production with scalable systems.

The turret systems 302a and 302b may be referred to herein as systems including turrets 306a and 306b, a plurality of workstations 316, and applicators 314 with nozzles 322 for sealant application. Each turret system (e.g. turret system 302a or 302b) may be adapted to receive lids from a starwheel (see, e.g., starwheels 520a and 520b in FIG. 5) which is adapted to receive the lids from a downstacker 304a and 304b. The turret systems 302a and 302b may be installed at the top of a table or platform surface 318 and rotate in opposition directions from one another (as depicted by the arrows). The turret systems 302a and 302b each include a plurality of workstations 316 which extend out from each turret system facing away from each other.

The workstations 316 receive an individual lid from a downstacker (e.g., downstacker 304a and 304b). In the dual turret system 300, there are two downstackers 304a and 304b, each downstacker 304a or 304b connected to each turret system 302a and 302b. The starwheels 520a and 520b adapted to deliver lids from each downstacker 304a and 304b to each turret 306a and 306b are rotatable in an opposite direction from its respective turret 306a and 306b, and in an opposite direction from the other starwheel 520b or 520a. Sealant injectors or applications 314 may be installed in the workstations 316 to apply sealant to each metal lid as the lids rotate around each turret 306a and 306b.

When applying sealant to a can end or container closure member, it may be desirable to closely control the lining time of the can ends. It may be beneficial to maximize the application time of sealant on can ends in order to ensure comprehensive coverage. In the disclosed technology, the downstackers 304a and 304b are located at the outer corner edges of the liner machine system, at approximately $\pm 45^\circ$ from the center axis of the turret, rather than directly opposite the exit chutes on the other side of the table or platform 318, to allow for additional lining time of the can ends.

When a lid or can end leaves a starwheel 520a or 520b, the can end is in a down position. The starwheel 520a or 520b rotates the lid around to meet a lower chuck 324. Specifically, each turret 306a and 306b includes a plurality of lower chucks 324 each configured to receive a lid, rotate the lid around the turret 306a and 306b and rotate the lid as the sealing compound is applied to the lid. The lower chucks 324 pick up the lid, and a lift cam 326a and 326b lifts the lower chuck 324 to a workstation 316 on the turret system 302a and 302b. The lift cam 324 includes a cam ring 350 and each lower chuck 324 includes a plurality of wheels 352 attached to each lower chuck 324 and configured to interface with the cam ring 350. The cam ring 350 is sized and shaped to raise each lower chuck 324 when the lower chuck 324 receives a lid such that the lid is positioned proximate a nozzle 322 to receive sealing compound. Additionally, the cam ring 350 is sized and shaped to lower each lower chuck 324 when the lower chuck 324 unloads a lid to an exit chute (see, e.g., exit chute 212a and 212b in FIG. 2). In the illustrated embodiment, the cam ring 350 includes a race (not shown) that has a variable height relative to the table or platform surface 318. The wheels 352 roll on the race and change the height of the lower chucks 324 as the lower chucks 324 rotate around the turret 306a and 306b.

When the lift cam 326 is in the up position, rising above the platform 318 to the applicator 314, the lid is rotated approximately 150° in the upright position, as the sealant is applied to the lid. In the disclosed technology, as a result of the locations of each downstacker, each lift cam 326 is

elongated. The longer length of the lift cam 326 allows for the lid or can end to be on the lift cam 326 longer, thus, allowing for more sealant application time. In other liner machine technology, lift cams are approximately 125° in duration (of a 360° rotation) in the upright position (not accounting for the up ramp and down ramp distance). In the disclosed technology, the lift cam 326 is approximately 150° degrees because of the distance from a downstacker 304a or 304b to the exit chute 212a or 212b.

Moreover, the longer length of the lift cam 326 enables the turret systems 302a and 302b to rotate at a higher rate. Specifically, some can end machines only rotate at approximately 150 rotations per minute (rpm). In contrast, the longer length of the lift cam 326 enables the turret systems 302a and 302b described herein to rotate at approximately 250 rpm, enabling the turret systems 302a and 302b to process more can ends or lids 490. Additionally, the longer length of the lift cam 326 also enables the lid or can end 490 to be rotated about the lower chuck 324 three times as the lid or can end 490 is rotated about the lift cam 326. Rotating the lid or can end 490 three times about the lower chuck 324 also enables more sealant to be applied to the lid or can end 490. In contrast, at least some known can end machines only rotate the can end or lid once or twice. Thus, the longer length of the lift cam 326 enables more sealant to be applied to the can end or lid 490 and enables the turret systems 302a and 302b to process more can ends or lids 490.

FIG. 4 illustrates an example of a turret liner machine system 400 in accordance with aspects of the present disclosure. Specifically, FIG. 4 is a bottom view of a synchronized dual turret liner machine system 400 for applying a sealing compound (not shown) to a can end or lid 490. The dual turret liner machine 400 applies a sealant to metal lids, each metal lid being received from a supply conveyor (not shown) and discharged to a discharge conveyor (not shown) via an exit chute 412a and 412b. The dual turret liner machine 400 includes two turret systems 402a and 402b driven by a single main drive motor 440. In some implementations, the liner machine technology may incorporate any number of turrets, drives, motors, chucks, chuck drives, downstackers, and starwheels. The disclosed technology is aimed at performing high speed and high-volume end production with scalable systems.

The turret systems 402a and 402b may be referred to herein as systems including turrets 406a and 406b, a plurality of workstations (see, e.g., workstations 116, 216, and 316 in FIGS. 1-3), and applicators (see, e.g., ten applicators 114, 214, and 314 in FIGS. 1-3) with nozzles (see, e.g., nozzles 122, 222, and 322 in FIGS. 1-3) for sealant application. Each turret system 402a and 402b may be adapted to receive lids from a starwheel (see, e.g., starwheels 520a and 520b in FIG. 5) which is adapted to receive the lids from a downstacker (e.g., downstackers 404a and 404b). The turret systems 402a and 402b may be installed at the top of a table or platform surface 418 and rotate in opposition directions from one another (as depicted by the arrows). The turret systems 402a and 402b each include a plurality of workstations (see, e.g., workstations 116, 216, and 316 in FIGS. 1-3) which extend out from each turret system facing away from each other.

The workstations receive an individual lid from a downstacker 404a and 404b. In the dual turret system 400, there are two downstackers 404a and 404b, each downstacker 404a and 404b connected to each turret system 402a and 402b. The starwheels 520a and 520b adapted to deliver lids from each downstacker 404a and 404b to each turret are rotatable in an opposite direction from its respective turret,

and in an opposite direction from the other starwheel 520b or 520a. Sealant injectors or applications may be installed in the workstations to apply sealant to each metal lid as the lids rotate around each turret.

When applying sealant to a can end or container closure member, it may be desirable to closely control the lining time of the can ends. It may be beneficial to maximize the application time of sealant on can ends in order to ensure comprehensive coverage. In the disclosed technology, the downstackers 404a and 404b are located at the outer corner edges of the liner machine system, at approximately $\pm 45^\circ$ from the center axis of the turret, rather than directly opposite the exit chutes on the other side of the table or platform, to allow for additional lining time of the can ends.

The turrets 406a and 406b each include a turret gear (e.g., a turret gear 430a or 430b), the main drive motor 440 includes a main drive gear 432, the turret liner machine system 400 includes two main drive driven gears 434a and 434b, the starwheels 520a and 520b each include a starwheel gear 436a and 436b, and the lower chucks 324 each include a lower chuck gear 438a and 438b. The turret gears 430a and 430b are configured to rotate the turrets 406a and 406b, the starwheel gears 436a and 436b are configured to rotate the starwheels 520a and 520b, and the lower chuck gears 438a and 438b are configured to rotate the lower chucks 324. In the illustrated embodiment, the main drive gear 432 is rotatably coupled to the turret gear 430b, the turret gear 430b is rotatably coupled to the main drive driven gear 434b and the starwheel gear 436b, the main drive driven gear 434b is rotatably coupled to the main drive driven gear 434a, the main drive driven gear 434a is rotatably coupled to the turret gear 430a, and the turret gear 430a is rotatably coupled to the starwheel gear 436b. In the illustrated embodiment, the lower chuck gear 438a and 438b are independently driven by a chuck gear motor (not shown). In alternative embodiments, the lower chuck gear 438a and 438b may be driven by the turret gears 430a and 430b, the starwheel gears 436a and 436b, the main drive gear 432, and/or the main drive driven gears 434a and 434b.

During operations, the main drive motor 440 rotates the main drive gear 432 which rotates the turret gear 430b. The turret gear 430b rotates the turret 406b, the main drive driven gear 434b, and the starwheel gear 436b. The starwheel gear 436b rotates the starwheel 520b. The main drive driven gear 434b rotates the main drive driven gear 434a which rotates the turret gear 430a. The turret gear 430a rotates the turret 406a and the starwheel gear 436a. The starwheel gear 436a rotates the starwheel 520a. Accordingly, in the illustrated embodiment, the turret gears 430a and 430b, the main drive gear 432, the main drive driven gears 434a and 434b, the starwheel gears 436a and 436b, and the lower chuck gears 438a and 438b are arranged to drive both turret systems 402a and 402b with a single main drive motor 440, reducing complexity, reducing auxiliary systems, and reducing the overall footprint of the turret liner machine system 400.

FIG. 5 illustrates an example of a turret liner machine system 500 in accordance with aspects of the present disclosure. Specifically, FIG. 5 is a top view of a synchronized dual turret liner machine system 500 for applying a sealing compound to a can end or lid 490 (shown in FIG. 4). The dual turret liner machine 500 applies a sealant to metal lids, each metal lid being received from a supply conveyor (not shown) and discharged to a discharge conveyor (not shown) via an exit chute 512. The dual turret liner machine 500 includes two turret systems 502a and 502b driven by a single main drive motor (see, e.g., main drive motor 440 in FIG. 4).

In some implementations, the liner machine technology may incorporate any number of turrets, drives, motors, chucks, chuck drives, downstackers, and starwheels. The disclosed technology is aimed at performing high speed and high-volume end production with scalable systems.

The turret systems **502a** and **502b** may be referred to herein as systems including a turret **506a** and **506b**, a plurality of workstations **516**, and applicators **514** with nozzles (see, e.g., nozzles **122** in FIG. 1) for sealant application. Each turret system **502a** and **502b** may be adapted to receive lids from a starwheel **520a** and **520b** which is adapted to receive the lids from a downstacker **504a** and **504b**). The turret systems **502a** and **502b** may be installed at the top of a table or platform surface **518** and rotate in opposition directions from one another (as depicted by the arrows). The turret systems **502a** and **502b** each include a plurality of workstations **516** which extend out from each turret system facing away from each other.

The workstations **516** receive an individual lid (not shown) from a downstacker **504a** and **504b**. In the dual turret system **500**, there are two downstackers **504a** and **504b**, each downstacker **504a** and **504b** connected to each turret system **502a** and **502b**. The starwheels **520a** and **520b** adapted to deliver lids from each downstacker to each turret **506a** and **506b** is rotatable in an opposite direction from its respective turret **506a** and **506b**, and in an opposite direction from the other starwheel **520b** or **520a**. Sealant injectors or applications **514** may be installed in the workstations **516** to apply sealant to each metal lid as the lids rotate around each turret.

When applying sealant to a can end or container closure member, it may be desirable to closely control the lining time of the can ends. It may be beneficial to maximize the application time of sealant on can ends in order to ensure comprehensive coverage. In the disclosed technology, the downstackers **504a** and **504b** are located at the outer corner edges of the liner machine system, at approximately $\pm 45^\circ$ from the center axis of the turret (as depicted with the arrows and axis line), rather than directly opposite the exit chutes **512a** and **512b** on the other side of the table or platform, to allow for additional lining time of the can ends.

FIG. 6 illustrates an example of a turret liner machine system **600** in accordance with aspects of the present disclosure. Specifically, FIG. 6 is a perspective view of a synchronized dual turret liner machine system **600** for applying a sealing compound to a can end or lid **790** (shown in FIG. 7). The synchronized dual turret liner machine **600** applies a sealant (not shown) to metal lids, each metal lid being received from a supply conveyor (not shown) and discharged to a discharge conveyor (not shown) via an exit chute (see, e.g., exit chute **712a** and **712b** in FIG. 7). In the illustrated embodiment, the dual turret liner machine **600** includes two turret systems **602a** and **602b** driven by a single main drive motor **640**. The main drive motor **640** located proximate to the first turret system may be configured to operate in conjunction with the main drive driven gear located proximate to the second turret system. In some implementations, the liner machine technology may incorporate any number of turrets, drives, motors, chucks, chuck drives, downstackers, and starwheels. The disclosed technology is aimed at performing high speed and high-volume end production with scalable systems.

The turret systems **602a** and **602b** may be referred to herein as systems including a turret **606a** and **606b**, a plurality of workstations **616**, and applicators **614** with nozzles **622** for sealant application. Each turret system may be adapted to receive lids from a starwheel (see, e.g.,

starwheels **1020a** and **1020b** in FIG. 10) which is adapted to receive the lids from a downstacker (e.g., downstackers **604a** and **604b**). The turret systems **602a** and **602b** may be installed at the top of a table or platform surface **618** and 5 rotate in opposition directions from one another (as depicted by the arrows). The turret systems **602a** and **602b** each include a plurality of workstations **616** which extend out from each turret system facing away from each other.

The workstations **616** receive an individual lid from a 10 downstacker. In the dual turret system **600**, there are two downstackers **604a** and **604b**, each downstacker connected to each turret system **602a** and **602b**. The starwheels **1020a** and **1020b** adapted to deliver lids from each downstacker to 15 each turret are rotatable in an opposite direction from its respective turret, and in an opposite direction from the other starwheel **1020b** or **1020a**. Sealant injectors or applications **614** may be installed in the workstations to apply sealant to each metal lid as the lids rotate around each turret **606a** and **606b**.

As shown in FIG. 6, a rod cage **610a** and **610b** is attached to each downstacker **604a** and **604b**. In some implementations, a rod cage **610a** and **610b** may not be used and a belt (not shown) or conveyor (not shown) feeds can ends directly 20 into the machine.

When applying sealant to a can end or container closure member, it may be desirable to closely control the lining time of the can ends. It may be beneficial to maximize the application time of sealant on can ends in order to ensure 25 comprehensive coverage. In the disclosed technology, the downstackers are located at the outer corner edges of the liner machine system, at approximately $\pm 45^\circ$ from the center axis of the turret **606a** and **606b** (as shown in more detail in FIG. 7, depicted with the arrows and axis line), rather than 30 directly opposite the exit chutes (see, e.g., exit chute **712a** and **712b** in FIG. 7) on the other side of the table or platform, to allow for additional lining time of the can ends.

As shown in FIG. 6, the turret liner machine system **600** includes two turret systems **602a** and **602b** operating in a 40 single machine. The two turret systems **602a** and **602b** share a plurality of auxiliary systems that enable the turret liner machine system **600** to reduce complexity, reduce auxiliary systems, and reduce the overall footprint of the turret liner machine system **600**. For example, the turret liner machine system **600** may include an electrical system (not shown), a compressed air system (not shown), an air cooler (not shown), an oil cooling system (not shown) including an oil cavity (not shown), and a feed of sealant (not shown). The arrangement of two turret systems **602a** and **602b** operating 45 in a single machine enables the two turret systems **602a** and **602b** to share the auxiliary systems, reducing complexity, reducing auxiliary systems, and reducing the overall footprint of the turret liner machine system **600**.

FIG. 7 illustrates an example of a turret liner machine 55 system **700** in accordance with aspects of the present disclosure. Specifically, FIG. 7 is a top view of a synchronized dual turret liner machine system **700** for applying a sealing compound to a can end or lid **790**. The dual turret liner machine **700** applies a sealant to metal lids, each metal lid 60 being received from a supply conveyor (not shown) and discharged to a discharge conveyor (not shown) via an exit chute **712a** and **712b**. The dual turret liner machine **700** includes two turret systems **702a** and **702b** driven by a single main drive motor (see, e.g., main drive motor **640** in FIG. 6). In some implementations, the liner machine technology may 65 incorporate any number of turrets, drives, motors, chucks, chuck drives, downstackers, and starwheels. The disclosed

technology is aimed at performing high speed and high-volume end production with scalable systems.

The turret systems **702a** and **702b** may be referred to herein as systems including a turret **706a** and **706b**, a plurality of workstations **716**, and applicators **714** with nozzles (see, e.g., nozzles **622** in FIG. 6) for sealant application. Each turret system **702a** and **702b** may be adapted to receive lids from a starwheel (see, e.g., starwheels **1020a** and **1020b** in FIG. 10) which is adapted to receive the lids from a downstacker **704a** and **704b**. The turret systems **702a** and **702b** may be installed at the top of a table or platform surface **718** and rotate in opposition directions from one another (as depicted by the arrows). The turret systems **702a** and **702b** each include a plurality of workstations **716** which extend out from each turret system facing away from each other.

The workstations **716** receive an individual lid (not shown) from a downstacker **704a** and **704b**. In the dual turret system **700**, there are two downstackers **704a** and **704b**, each downstacker **704a** and **704b** connected to each turret system **702a** and **702b**. The starwheels **1020a** and **1020b** adapted to deliver lids from each downstacker to each turret **706a** and **706b** are rotatable in an opposite direction from its respective turret **706a** and **706b**, and in an opposite direction from the other starwheel **1020b** or **1020a**. Sealant injectors or applications **714** may be installed in the workstations **716** to apply sealant to each metal lid as the lids rotate around each turret.

When applying sealant to a can end or container closure member, it may be desirable to closely control the lining time of the can ends. It may be beneficial to maximize the application time of sealant on can ends in order to ensure comprehensive coverage. In the disclosed technology, the downstackers **704a** and **704b** are located at the outer corner edges of the liner machine system, at approximately $\pm 45^\circ$ from the center axis of the turret (as depicted with the arrows and axis line), rather than directly opposite the exit chutes **712a** and **712b** on the other side of the table or platform, to allow for additional lining time of the can ends.

FIG. 8 illustrates an example of a turret liner machine system **800** in accordance with aspects of the present disclosure. Specifically, FIG. 8 is a side view of a synchronized dual turret liner machine system **800** for applying a sealing compound to a can end or lid **790** (shown in FIG. 7). The dual turret liner machine **800** applies a sealant to metal lids, each metal lid being received from a supply conveyor (not shown) and discharged to a discharge conveyor (not shown) via an exit chute (see, e.g., exit chute **712a** and **712b** in FIG. 7). The dual turret liner machine **800** includes two turret systems **802a** and **802b** driven by a single main drive motor **840**. In some implementations, the liner machine technology may incorporate any number of turrets, drives, motors, chucks, chuck drives, downstackers, and starwheels. The disclosed technology is aimed at performing high speed and high-volume end production with scalable systems.

The turret systems **802a** and **802b** may be referred to herein as systems including a turret **806a** and **806b**, a plurality of workstations **816**, and applicators **814** with nozzles **822** for sealant application. Each turret system **802a** and **802b** may be adapted to receive lids from a starwheel (see, e.g., starwheels **1020a** and **1020b** in FIG. 10) which is adapted to receive the lids from a downstacker **804a** and **804b**. The turret systems **802a** and **802b** may be installed at the top of a table or platform surface **818** and rotate in opposition directions from one another (as depicted by the arrows). The turret systems **802a** and **802b** each include a

plurality of workstations **816** which extend out from each turret system facing away from each other.

The workstations **816** receive an individual lid from a downstacker **804a** and **804b**. In the dual turret system **800**, there are two downstackers **804a** and **804b**, each downstacker **804a** and **804b** connected to each turret system **802a** and **802b**. The starwheels **1020a** or **1020b** adapted to deliver lids from each downstacker **804a** and **804b** to each turret **806a** and **806b** are rotatable in an opposite direction from its respective turret **806a** and **806b**, and in an opposite direction from the other starwheel **1020b** or **1020a**. Sealant injectors or applications **814** may be installed in the workstations **816** to apply sealant to each metal lid as the lids rotate around each turret **806a** and **806b**.

When applying sealant to a can end or container closure member, it may be desirable to closely control the lining time of the can ends. It may be beneficial to maximize the application time of sealant on can ends in order to ensure comprehensive coverage. In the disclosed technology, the downstackers **804a** and **804b** are located at the outer corner edges of the liner machine system, at approximately $\pm 45^\circ$ from the center axis of the turret, rather than directly opposite the exit chutes on the other side of the table or platform **818**, to allow for additional lining time of the can ends.

When a lid or can end leaves a starwheel **1020a** or **1020b**, the can end is in a down position. The starwheel **1020a** or **1020b** rotates the lid around to meet a lower chuck **824**. Specifically, each turret **806a** and **806b** includes a plurality of lower chucks **824** each configured to receive a lid, rotate the lid around the turret **806a** and **806b** and rotate the lid as the sealing compound is applied to the lid. The lower chucks **824** pick up the lid, and a lift cam **826a** and **826b** lifts the lower chuck **824** to a workstation **816** on the turret system **802a** and **802b**. The lift cam **824** includes a cam ring **850** and each lower chuck **824** includes a plurality of wheels **852** attached to each lower chuck **824** and configured to interface with the cam ring **850**. The cam ring **850** is sized and shaped to raise each lower chuck **824** when the lower chuck **824** receives a lid such that the lid is positioned proximate a nozzle **822** to receive sealing compound. Additionally, the cam ring **850** is sized and shaped to lower each lower chuck **824** when the lower chuck **824** unloads a lid to an exit chute (see, e.g., exit chute **712a** and **712b** in FIG. 7). In the illustrated embodiment, the cam ring **850** includes a race (not shown) that has a variable height relative to the table or platform surface **818**. The wheels **852** roll on the race and change the height of the lower chucks **824** as the lower chucks **824** rotate around the turret **806a** and **806b**.

When the lift cam **826** is in the up position, rising above the platform **818** to the applicator **814**, the lid is rotated approximately 150° in the upright position, as the sealant is applied to the lid. In the disclosed technology, as a result of the locations of each downstacker, each lift cam **826** is longer. The longer length of the lift cam **826** allows for the lid or can end to be on the lift cam **826** longer, thus, allowing for more sealant application time. In other liner machine technology, lift cams are approximately 125° in duration (of a 360° rotation) in the upright position (not accounting for the up ramp and down ramp distance). In the disclosed technology, the lift cams **826** are approximately 150° degrees because of the distance from a downstacker **804a** and **804b** to the exit chute **712a** and **712b**.

Moreover, the longer length of the lift cam **826** enables the turret systems **802a** and **802b** to rotate at a higher rate. Specifically, some can end machines only rotate at 150° rotations per minute (rpm). In contrast, the longer length of

the lift cam 826 enables the turret systems 802a and 802b described herein to rotate at 250 rpm, enabling the turret systems 802a and 802b to process more can ends or lids 790. Additionally, the longer length of the lift cam 826 also enables the lid or can end 790 to be rotated about the lower chuck 824 three times as the lid or can end 790 is rotated about the lift cam 826. Rotating the lid or can end 790 three times about the lower chuck 824 also enables more sealant to be applied to the lid or can end 790. In contrast, at least some known can end machines only rotate the can end or lid once or twice. Thus, the longer length of the lift cam 826 enables more sealant to be applied to the can end or lid 790 and enables the turret systems 802a and 802b to process more can ends or lids 790.

FIG. 9 illustrates an example of a turret liner machine system 900 in accordance with aspects of the present disclosure. Specifically, FIG. 9 is a bottom view of a synchronized dual turret liner machine system 900 for applying a sealing compound (not shown) to a can end or lid 790 (shown in FIG. 7). The dual turret liner machine 900 applies a sealant to metal lids, each metal lid being received from a supply conveyor (not shown) and discharged to a discharge conveyor (not shown) via an exit chute 912a and 912b. The dual turret liner machine 900 includes two turret systems 902a and 902b driven by a single main drive motor 940. In some implementations, the liner machine technology may incorporate any number of turrets, drives, motors, chucks, chuck drives, downstackers, and starwheels. The disclosed technology is aimed at performing high speed and high-volume end production with scalable systems.

The turret systems 902a and 902b may be referred to herein as systems including a turret 906a and 906b, a plurality of workstations (see, e.g., workstations 616, 716, and 816 in FIGS. 6-8), and applicators (see, e.g., applicators 614, 714, and 814 in FIGS. 6-8) with nozzles (see, e.g., applicators 622, 722, and 822 in FIGS. 6-8) for sealant application. Each turret system 902a and 902b may be adapted to receive lids from a starwheel (see, e.g., starwheels 1020a and 1020b in FIG. 10) which is adapted to receive the lids from a downstacker (e.g., downstackers 904a and 904b). The turret systems 902a and 902b may be installed at the top of a table or platform surface 918 and rotate in opposition directions from one another (as depicted by the arrows). The turret systems 902a and 902b each include a plurality of workstations (see, e.g., workstations 616, 716, and 816 in FIGS. 6-8) which extend out from each turret system facing away from each other.

The workstations receive an individual lid from a downstacker 904a and 904b. In the dual turret system 900, there are two downstackers 904a and 904b, each downstacker 904a and 904b connected to each turret system 902a and 902b. The starwheels 1020a and 1020b adapted to deliver lids from each downstacker 904a and 904b to each turret are rotatable in an opposite direction from its respective turret, and in an opposite direction from the other starwheel 1020b or 1020a. Sealant injectors or applications may be installed in the workstations to apply sealant to each metal lid as the lids rotate around each turret.

When applying sealant to a can end or container closure member, it may be desirable to closely control the lining time of the can ends. It may be beneficial to maximize the application time of sealant on can ends in order to ensure comprehensive coverage. In the disclosed technology, the downstackers 904a and 904b are located at the outer corner edges of the liner machine system, at approximately $\pm 45^\circ$ from the center axis of the turret, rather than directly

opposite the exit chutes on the other side of the table or platform, to allow for additional lining time of the can ends.

The turrets 906a and 906b each include a turret gear 930a and 930b, the main drive motor 940 includes a main drive gear 932, the turret liner machine system 900 includes a main drive driven gear 934, the starwheels 1020a or 1020b each include a starwheel gear 936a and 936b, and the lower chucks 824 each include a lower chuck gear 938a and 938b. The turret gears 930a and 930b are configured to rotate the turrets 906a and 906b, the starwheel gears 936a and 936b are configured to rotate the starwheels 1020a or 1020b, and the lower chuck gears 938a and 938b are configured to rotate the lower chucks 824. In the illustrated embodiment, the main drive gear 932 is rotatably coupled to the turret gear 930b and the main drive driven gear 934, the turret gear 930b is rotatably coupled to the starwheel gear 936b, the main drive driven gear 934 is rotatably coupled to the turret gear 930a, and the turret gear 930a is rotatably coupled to the starwheel gear 936b. In the illustrated embodiment, the lower chuck gear 938a and 938b are independently driven by a chuck gear motor (not shown). In alternative embodiments, the lower chuck gear 938a and 938b may be driven by the turret gears 930a and 930b, the starwheel gears 936a and 936b, the main drive gear 932, and/or the main drive driven gear 934.

During operations, the main drive motor 940 rotates the main drive gear 932 which rotates the turret gear 930b and the main drive driven gear 934. The turret gear 930b rotates the turret 906b and the starwheel gear 936b which rotates the starwheel 1020b. The main drive driven gear 934 rotates the turret gear 930a. The turret gear 930a rotates the turret 906a and the starwheel gear 936a. The starwheel gear 936a rotates the starwheel 1020a. Accordingly, in the illustrated embodiment, the turret gears 930a and 930b, the main drive gear 932, the main drive driven gears 934, the starwheel gears 936a and 936b, and the lower chuck gears 938a and 938b are arranged to drive both turret systems 902a and 902b with a single main drive motor 940, reducing complexity, reducing auxiliary systems, and reducing the overall footprint of the turret liner machine system 900.

FIG. 10 illustrates an example of a turret liner machine system 1000 in accordance with aspects of the present disclosure. Specifically, FIG. 10 is a top view of a synchronized dual turret liner machine system 1000 for applying a sealing compound to a can end or lid 790 (shown in FIG. 7). The dual turret liner machine 1000 applies a sealant to metal lids, each metal lid being received from a supply conveyor (not shown) and discharged to a discharge conveyor (not shown) via an exit chute 1012. The dual turret liner machine 1000 includes two turret systems 1002a and 1002b driven by a single main drive motor (see, e.g., main drive motor 940 in FIG. 9). In some implementations, the liner machine technology may incorporate any number of turrets, drives, motors, chucks, chuck drives, downstackers, and starwheels. The disclosed technology is aimed at performing high speed and high-volume end production with scalable systems.

The turret systems 1002a and 1002b may be referred to herein as systems including a turret 1006a and 1006b, a plurality of workstations 1016, and applicators 1014 with nozzles (see, e.g., nozzles 622 in FIG. 6) for sealant application. Each turret system 1002a and 1002b may be adapted to receive lids from a starwheel 1020a and 1020b which is adapted to receive the lids from a downstacker 1004a and 1004b. The turret systems 1002a and 1002b may be installed at the top of a table or platform surface 1018 and rotate in opposition directions from one another (as depicted by the arrows). The turret systems 1002a and 1002b each

include a plurality of workstations 1016 which extend out from each turret system facing away from each other.

The workstations 1016 receive an individual lid (not shown) from a downstacker 1004a and 1004b. In the dual turret system 1000, there are two downstackers 1004a and 1004b, each downstacker 1004a and 1004b connected to each turret system 1002a and 1002b. The starwheels 1020a and 1020b adapted to deliver lids from each downstacker to each turret 1006a and 1006b is rotatable in an opposite direction from its respective turret 1006a and 1006b, and in an opposite direction from the other starwheel 1020b or 1020a. Sealant injectors or applications 1014 may be installed in the workstations 1016 to apply sealant to each metal lid as the lids rotate around each turret.

When applying sealant to a can end or container closure member, it may be desirable to closely control the lining time of the can ends. It may be beneficial to maximize the application time of sealant on can ends in order to ensure comprehensive coverage. In the disclosed technology, the downstackers 1004a and 1004b are located at the outer corner edges of the liner machine system, at approximately $\pm 45^\circ$ from the center axis of the turret (as depicted with the arrows and axis line), rather than directly opposite the exit chutes 1012a and 1012b on the other side of the table or platform, to allow for additional lining time of the can ends.

As shown in FIG. 10, the turret liner machine system 1000 includes two turret systems 1002a and 1002b operating in a single machine. The two turret systems 1002a and 1002b share a plurality of auxiliary systems that enable the turret liner machine system 1000 to reduce complexity, reduce auxiliary systems, and reduce the overall footprint of the turret liner machine system 1000. For example, the turret liner machine system 1000 may include an electrical system (not shown), a compressed air system (not shown), an air cooler (not shown), an oil cooling system (not shown) including an oil cavity (not shown), and a feed of sealant (not shown). The arrangement of two turret systems 1002a and 1002b operating in a single machine enables the two turret systems 1002a and 1002b to share the auxiliary systems, reducing complexity, reducing auxiliary systems, and reducing the overall footprint of the turret liner machine system 1000.

FIG. 11 illustrates an example of a turret liner machine system 1100 in accordance with aspects of the present disclosure. Specifically, FIG. 11 is a perspective view of an asynchronized dual turret liner machine system 1100 for applying a sealing compound to a can end or lid 1290 (shown in FIG. 12). The asynchronized dual turret liner machine 1100 applies a sealant (not shown) to metal lids, each metal lid being received from a supply conveyor (not shown) and discharged to a discharge conveyor (not shown) via an exit chute (see, e.g., exit chute 1212a and 1212b in FIG. 12). In the illustrated embodiment, the dual turret liner machine 1100 includes two turret systems 1102a and 1102b driven by two independent main drive motors 1140a and 1140b. The main drive motors 1140a and 1140b are located proximate to the respective turret systems and may be configured to operate independently of each other to ensure that if one of the turret systems requires maintenance or breaks down, the other turret system can continue to operate, increasing production time and increasing profits. In some implementations, the liner machine technology may incorporate any number of turrets, drives, motors, chucks, chuck drives, downstackers, and starwheels. The disclosed technology is aimed at performing high speed and high-volume end production with scalable systems.

FIGS. 11-15 illustrates an example of an asynchronized or independent turret liner machine system in accordance with aspects of the present disclosure. Specifically, FIGS. 11-15 illustrate an independent turret liner machine system. Independent turret systems are configured where the first turret and its respective starwheel operate independently from the second turret. For example, the first turret and its respective starwheel may be operating while the second turret and its respective starwheel do not operate. This independent operation allows for access, downtime, and maintenance to one of the turrets and its respective system. In another example, the first turret and its respective starwheel may be operating while the second turret and its respective starwheel operate, yet each turret has the capability of operating or not operating when the other turret is operating. The advantages of independent turret liner machine systems are that one system if one system fails or is turned off for maintenance, the other system may operate, resulting in less time and money lost.

The turret systems 1102a and 1102b may be referred to herein as systems including a turret 1106a and 1106b, a plurality of workstations 1116, and applicators 1114 with nozzles 1122 for sealant application. Each turret system may be adapted to receive lids from a starwheel (see, e.g., starwheels 1520a and 1520b in FIG. 15) which is adapted to receive the lids from a downstacker (e.g., downstackers 1104a and 1104b). The turret systems 1102a and 1102b may be installed at the top of a table or platform surface 1118 and rotate in opposition directions from one another (as depicted by the arrows). The turret systems 1102a and 1102b each include a plurality of workstations 1116 which extend out from each turret system facing away from each other.

The workstations 1116 receive an individual lid from a downstacker. In the dual turret system 1100, there are two downstackers 1104a and 1104b, each downstacker connected to each turret system 1102a and 1102b. The starwheels 1520a and 1520b adapted to deliver lids from each downstacker to each turret are rotatable in an opposite direction from its respective turret, and in an opposite direction from the other starwheel 1520b or 1520a. Sealant injectors or applications 1114 may be installed in the workstations to apply sealant to each metal lid as the lids rotate around each turret 1106a and 1106b.

As shown in FIG. 11, a rod cage 1110a and 1110b is attached to each downstacker 1104a and 1104b. In some implementations, a rod cage 1110a and 1110b may not be used and a belt (not shown) or conveyor (not shown) feeds can ends directly into the machine.

When applying sealant to a can end or container closure member, it may be desirable to closely control the lining time of the can ends. It may be beneficial to maximize the application time of sealant on can ends in order to ensure comprehensive coverage. In the disclosed technology, the downstackers are located at the outer corner edges of the liner machine system, at approximately $\pm 45^\circ$ from the center axis of the turret 1106a and 1106b (as shown in more detail in FIG. 12, depicted with the arrows and axis line), rather than directly opposite the exit chutes (see, e.g., exit chute 1212a and 1212b in FIG. 12) on the other side of the table or platform, to allow for additional lining time of the can ends.

FIG. 12 illustrates an example of a turret liner machine system 1200 in accordance with aspects of the present disclosure. Specifically, FIG. 12 is a top view of an asynchronized dual turret liner machine system 1200 for applying a sealing compound to a can end or lid 1290. The dual turret liner machine 1200 applies a sealant to metal lids, each

metal lid being received from a supply conveyor (not shown) and discharged to a discharge conveyor (not shown) via an exit chute 1212a and 1212b. The dual turret liner machine 1200 includes two turret systems 1202a and 1202b driven by two main drive motors (see, e.g., main drive motors 1140a and 1140b in FIG. 11). In some implementations, the liner machine technology may incorporate any number of turrets, drives, motors, chucks, chuck drives, downstackers, and starwheels. The disclosed technology is aimed at performing high speed and high-volume end production with scalable systems.

The turret systems 1202a and 1202b may be referred to herein as systems including a turret 1206a and 1206b, a plurality of workstations 1216, and applicators 1214 with nozzles (see, e.g., nozzles 1122 in FIG. 11) for sealant application. Each turret system 1202a and 1202b may be adapted to receive lids from a starwheel (see, e.g., starwheels 1520a and 1520b in FIG. 15) which is adapted to receive the lids from a downstacker 1204a and 1204b. The turret systems 1202a and 1202b may be installed at the top of a table or platform surface 1218 and rotate in opposition directions from one another (as depicted by the arrows). The turret systems 1202a and 1202b each include a plurality of workstations 1216 which extend out from each turret system facing away from each other.

The workstations 1216 receive an individual lid (not shown) from a downstacker 1204a and 1204b. In the dual turret system 1200, there are two downstackers 1204a and 1204b, each downstacker 1204a and 1204b connected to each turret system 1202a and 1202b. The starwheels 1520a and 1520b adapted to deliver lids from each downstacker to each turret 1206a and 1206b are rotatable in an opposite direction from its respective turret 1206a and 1206b, and in an opposite direction from the other starwheel 1520b or 1520a. Sealant injectors or applications 1214 may be installed in the workstations 1216 to apply sealant to each metal lid as the lids rotate around each turret.

When applying sealant to a can end or container closure member, it may be desirable to closely control the lining time of the can ends. It may be beneficial to maximize the application time of sealant on can ends in order to ensure comprehensive coverage. In the disclosed technology, the downstackers 1204a and 1204b are located at the outer corner edges of the liner machine system, at approximately $\pm 45^\circ$ from the center axis of the turret (as depicted with the arrows and axis line), rather than directly opposite the exit chutes 1212a and 1212b on the other side of the table or platform, to allow for additional lining time of the can ends.

FIG. 13 illustrates an example of a turret liner machine system 1300 in accordance with aspects of the present disclosure. Specifically, FIG. 13 is a side view of an asynchronous dual turret liner machine system 1300 for applying a sealing compound to a can end or lid 1290 (shown in FIG. 12). The dual turret liner machine 1300 applies a sealant to metal lids, each metal lid being received from a supply conveyor (not shown) and discharged to a discharge conveyor (not shown) via an exit chute (see, e.g., exit chute 1212a and 1212b in FIG. 12). The dual turret liner machine 1300 includes two turret systems 1302a and 1302b driven by two main drive motors 1340a and 1340b. In some implementations, the liner machine technology may incorporate any number of turrets, drives, motors, chucks, chuck drives, downstackers, and starwheels. The disclosed technology is aimed at performing high speed and high-volume end production with scalable systems.

The turret systems 1302a and 1302b may be referred to herein as systems including a turret 1306a and 1306b, a

plurality of workstations 1316, and applicators 1314 with nozzles 1322 for sealant application. Each turret system 1302a and 1302b may be adapted to receive lids from a starwheel (see, e.g., starwheels 1520a and 1520b in FIG. 15) which is adapted to receive the lids from a downstacker 1304a and 1304b. The turret systems 1302a and 1302b may be installed at the top of a table or platform surface 1318 and rotate in opposition directions from one another (as depicted by the arrows). The turret systems 1302a and 1302b each include a plurality of workstations 1316 which extend out from each turret system facing away from each other.

The workstations 1316 receive an individual lid from a downstacker 1304a and 1304b. In the dual turret system 1300, there are two downstackers 1304a and 1304b, each downstacker 1304a and 1304b connected to each turret system 1302a and 1302b. The starwheels 1520a or 1520b adapted to deliver lids from each downstacker 1304a and 1304b to each turret 1306a and 1306b are rotatable in an opposite direction from its respective turret 1306a and 1306b, and in an opposite direction from the other starwheel 1520b or 1520a. Sealant injectors or applications 1314 may be installed in the workstations 1316 to apply sealant to each metal lid as the lids rotate around each turret 1306a and 1306b.

When applying sealant to a can end or container closure member, it may be desirable to closely control the lining time of the can ends. It may be beneficial to maximize the application time of sealant on can ends in order to ensure comprehensive coverage. In the disclosed technology, the downstackers 1304a and 1304b are located at the outer corner edges of the liner machine system, at approximately $\pm 45^\circ$ from the center axis of the turret, rather than directly opposite the exit chutes on the other side of the table or platform 1318, to allow for additional lining time of the can ends.

When a lid or can end leaves a starwheel 1520a or 1520b, the can end is in a down position. The starwheel 1520a or 1520b rotates the lid around to meet a lower chuck 1324. Specifically, each turret 1306a and 1306b includes a plurality of lower chucks 1324 each configured to receive a lid, rotate the lid around the turret 1306a and 1306b and rotate the lid as the sealing compound is applied to the lid. The lower chucks 1324 pick up the lid, and a lift cam 1326a and 1326b lifts the lower chuck 1324 to a workstation 1316 on the turret system 1302a and 1302b. The lift cam 1324 includes a cam ring 1350 and each lower chuck 1324 includes a plurality of wheels 1352 attached to each lower chuck 1324 and configured to interface with the cam ring 1350. The cam ring 1350 is sized and shaped to raise each lower chuck 1324 when the lower chuck 1324 receives a lid such that the lid is positioned proximate a nozzle 1322 to receive sealing compound. Additionally, the cam ring 1350 is sized and shaped to lower each lower chuck 1324 when the lower chuck 1324 unloads a lid to an exit chute (see, e.g., exit chute 1212a and 1212b in FIG. 12). In the illustrated embodiment, the cam ring 1350 includes a race (not shown) that has a variable height relative to the table or platform surface 1318. The wheels 1352 roll on the race and change the height of the lower chucks 1324 as the lower chucks 1324 rotate around the turret 1306a and 1306b.

When the lift cam 1326 is in the up position, rising above the platform 1318 to the applicator 1314, the lid is rotated approximately 150° in the upright position, as the sealant is applied to the lid. In the disclosed technology, as a result of the locations of each downstacker, each lift cam 1326 is elongated. The longer length of the lift cam 1326 allows for the lid or can end to be on the lift cam 1326 longer, thus,

allowing for more sealant application time. In other liner machine technology, lift cams are approximately 125° in duration (of a 360° rotation) in the upright position (not accounting for the up ramp and down ramp distance). In the disclosed technology, the lift cams 1326 are approximately 150° degrees because of the distance from a downstacker 1304a and 1304b to the exit chute 1212a and 1212b.

Moreover, the longer length of the lift cam 1326 enables the turret systems 1302a and 1302b to rotate at a higher rate. Specifically, some can end machines only rotate at 150 rotations per minute (rpm). In contrast, the longer length of the lift cam 1326 enables the turret systems 1302a and 1302b described herein to rotate at 250 rpm, enabling the turret systems 1302a and 1302b to process more can ends or lids 1290. Additionally, the longer length of the lift cam 1326 also enables the lid or can end 1290 to be rotated about the lower chuck 1324 three times as the lid or can end 1290 is rotated about the lift cam 1326. Rotating the lid or can end 1290 three times about the lower chuck 1324 also enables more sealant to be applied to the lid or can end 1290. In contrast, at least some known can end machines only rotate the can end or lid once or twice. Thus, the longer length of the lift cam 1326 enables more sealant to be applied to the can end or lid 1290 and enables the turret systems 1302a and 1302b to process more can ends or lids 1290.

FIG. 14 illustrates an example of a turret liner machine system 1400 in accordance with aspects of the present disclosure. Specifically, FIG. 14 is a bottom view of an asynchronized dual turret liner machine system 1400 for applying a sealing compound (not shown) to a can end or lid 1290 (shown in FIG. 12). The dual turret liner machine 1400 applies a sealant to metal lids, each metal lid being received from a supply conveyor (not shown) and discharged to a discharge conveyor (not shown) via an exit chute 1412a and 1412b. The dual turret liner machine 1400 includes two turret systems 1402a and 1402b driven by two main drive motors 1440a and 1440b. In some implementations, the liner machine technology may incorporate any number of turrets, drives, motors, chucks, chuck drives, downstackers, and starwheels. The disclosed technology is aimed at performing high speed and high-volume end production with scalable systems.

The turret systems 1402a and 1402b may be referred to herein as systems including a turret 1406a and 1406b, a plurality of workstations (see, e.g., workstations 1116, 1216, and 1316 in FIGS. 11-13), and applicators (see, e.g., applicators 1114, 1214, and 1314 in FIGS. 11-13) with nozzles (see, e.g., applicators 1122, 1222, and 1322 in FIGS. 11-13) for sealant application. Each turret system 1402a and 1402b may be adapted to receive lids from a starwheel (see, e.g., starwheels 1520a and 1520b in FIG. 15) which is adapted to receive the lids from a downstacker (e.g., downstackers 1404a and 1404b). The turret systems 1402a and 1402b may be installed at the top of a table or platform surface 1418 and rotate in opposition directions from one another (as depicted by the arrows). The turret systems 1402a and 1402b each include a plurality of workstations (see, e.g., workstations 1116, 1216, and 1316 in FIGS. 11-13) which extend out from each turret system facing away from each other.

The workstations receive an individual lid from a downstacker 1404a and 1404b. In the dual turret system 1400, there are two downstackers 1404a and 1404b, each downstacker 1404a and 1404b connected to each turret system 1402a and 1402b. The starwheels 1520a and 1520b adapted to deliver lids from each downstacker 1404a and 1404b to each turret are rotatable in an opposite direction from its respective turret, and in an opposite direction from the other

starwheel 1520b or 1520a. Sealant injectors or applications may be installed in the workstations to apply sealant to each metal lid as the lids rotate around each turret.

When applying sealant to a can end or container closure member, it may be desirable to closely control the lining time of the can ends. It may be beneficial to maximize the application time of sealant on can ends in order to ensure comprehensive coverage. In the disclosed technology, the downstackers 1404a and 1404b are located at the outer corner edges of the liner machine system, at approximately ±45° from the center axis of the turret, rather than directly opposite the exit chutes on the other side of the table or platform, to allow for additional lining time of the can ends.

The turrets 1406a and 1406b each include a turret gear 1430a and 1430b, the main drive motors 1440a and 1440b each include a main drive gear 1432a and 1432b, the starwheels 1520a or 1520b each include a starwheel gear 1436a and 1436b, and the lower chucks 1324 each include a lower chuck gear 1438a and 1438b. The turret gears 1430a and 1430b are configured to rotate the turrets 1406a and 1406b, the starwheel gears 1436a and 1436b are configured to rotate the starwheels 1520a or 1520b, and the lower chuck gears 1438a and 1438b are configured to rotate the lower chucks 1324. In the illustrated embodiment, the main drive gears 1432a and 1432b are rotatably coupled to the turret gears 1430a and 1430b respectively. The turret gears 1430a and 1430b are rotatably coupled to the starwheel gear 1436a and 1436b respectively. In the illustrated embodiment, the lower chuck gear 1438a and 1438b are independently driven by a chuck gear motor (not shown). In alternative embodiments, the lower chuck gear 1438a and 1438b may be driven by the turret gears 1430a and 1430b, the starwheel gears 1436a and 1436b, and/or the main drive gears 1432a and 1432b.

During operations, the main drive motors 1440a and 1440b rotate the 1432a and 1432b which rotate the turret gears 1430a and 1430b respectively. The turret gears 1430a and 1430b rotate the turrets 1406a and 1406b and the starwheel gears 1436a and 1436b respectfully. The starwheel gears 1436a and 1436b rotate the starwheels 1520a and 1520b. Accordingly, in the illustrated embodiment, the turret gears 1430a and 1430b, the main drive gear 1432a and 1432b, the starwheel gears 1436a and 1436b, and the lower chuck gears 1438a and 1438b are arranged to drive both turret systems 1402a and 1402b with two main drive motors 1440a and 1440b, increasing production time, increasing profits, and reducing the overall footprint of the turret liner machine system 1400.

FIG. 15 illustrates an example of a turret liner machine system 1500 in accordance with aspects of the present disclosure. Specifically, FIG. 15 is a top view of an asynchronized dual turret liner machine system 1500 for applying a sealing compound to a can end or lid 1290 (shown in FIG. 12). The dual turret liner machine 1500 applies a sealant to metal lids, each metal lid being received from a supply conveyor (not shown) and discharged to a discharge conveyor (not shown) via an exit chute 1512. The dual turret liner machine 1500 includes two turret systems 1502a and 1502b driven by two main drive motors (see, e.g., main drive motor 1440a and 1440b in FIG. 14). In some implementations, the liner machine technology may incorporate any number of turrets, drives, motors, chucks, chuck drives, downstackers, and starwheels. The disclosed technology is aimed at performing high speed and high-volume end production with scalable systems.

FIGS. 15-20 illustrates an example of an asynchronized or independent turret liner machine system in accordance with

aspects of the present disclosure. Specifically, FIGS. 15-20 illustrate an independent turret liner machine system. Independent turret systems are configured where the first turret and its respective starwheel operate independently from the second turret. For example, the first turret and its respective starwheel may be operating while the second turret and its respective starwheel do not operate. This independent operation allows for access, downtime, and maintenance to one of the turrets and its respective system. In another example, the first turret and its respective starwheel may be operating while the second turret and its respective starwheel operate, yet each turret has the capability of operating or not operating when the other turret is operating. The advantages of independent turret liner machine systems are that one system if one system fails or is turned off for maintenance, the other system may operate, resulting in less time and money lost.

The turret systems 1502a and 1502b may be referred to herein as systems including a turret 1506a and 1506b, a plurality of workstations 1516, and applicators 1514 with nozzles (see, e.g., nozzles 1122 in FIG. 11) for sealant application. Each turret system 1502a and 1502b may be adapted to receive lids from a starwheel 1520a and 1520b which is adapted to receive the lids from a downstacker 1504a and 1504b). The turret systems 1502a and 1502b may be installed at the top of a table or platform surface 1518 and rotate in opposition directions from one another (as depicted by the arrows). The turret systems 1502a and 1502b each include a plurality of workstations 1516 which extend out from each turret system facing away from each other.

The workstations 1516 receive an individual lid (not shown) from a downstacker 1504a and 1504b. In the dual turret system 1500, there are two downstackers 1504a and 1504b, each downstacker 1504a and 1504b connected to each turret system 1502a and 1502b. The starwheels 1520a and 1520b adapted to deliver lids from each downstacker to each turret 1506a and 1506b is rotatable in an opposite direction from its respective turret 1506a and 1506b, and in an opposite direction from the other starwheel 1520b or 1520a. Sealant injectors or applications 1514 may be installed in the workstations 1516 to apply sealant to each metal lid as the lids rotate around each turret.

When applying sealant to a can end or container closure member, it may be desirable to closely control the lining time of the can ends. It may be beneficial to maximize the application time of sealant on can ends in order to ensure comprehensive coverage. In the disclosed technology, the downstackers 1504a and 1504b are located at the outer corner edges of the liner machine system, at approximately $\pm 45^\circ$ from the center axis of the turret (as depicted with the arrows and axis line), rather than directly opposite the exit chutes 1512a and 1512b on the other side of the table or platform, to allow for additional lining time of the can ends.

As shown in FIG. 15, the turret liner machine system 1500 includes two turret systems 1502a and 1502b operating in a single machine. The two turret systems 1502a and 1502b share a plurality of auxiliary systems that enable the turret liner machine system 1500 to reduce complexity, reduce auxiliary systems, and reduce the overall footprint of the turret liner machine system 1500. For example, the turret liner machine system 1500 may include an electrical system (not shown), a compressed air system (not shown), an air cooler (not shown), an oil cooling system (not shown) including an oil cavity (not shown), and a feed of sealant (not shown). The arrangement of two turret systems 1502a and 1502b operating in a single machine enables the two turret systems 1502a and 1502b to share the auxiliary

systems, reducing complexity, reducing auxiliary systems, and reducing the overall footprint of the turret liner machine system 1500.

FIG. 16 illustrates an example of a turret liner machine system 1600 in accordance with aspects of the present disclosure. Specifically, FIG. 16 is a perspective view of an asynchronized dual turret liner machine system 1600 for applying a sealing compound to a can end or lid 1790 (shown in FIG. 17). The asynchronized dual turret liner machine 1600 applies a sealant (not shown) to metal lids, each metal lid being received from a supply conveyor (not shown) and discharged to a discharge conveyor (not shown) via an exit chute (see, e.g., exit chute 1712a and 1712b in FIG. 17). In the illustrated embodiment, the dual turret liner machine 1600 includes two turret systems 1602a and 1602b driven by two independent main drive motors 1640a and 1640b. The main drive motors 1640a and 1640b are located proximate to the respective turret systems and may be configured to operate independently of each other to ensure that if one of the turret systems requires maintenance or breaks down, the other turret system can continue to operate, increasing production time and increasing profits. In some implementations, the liner machine technology may incorporate any number of turrets, drives, motors, chucks, chuck drives, downstackers, and starwheels. The disclosed technology is aimed at performing high speed and high-volume end production with scalable systems.

The turret systems 1602a and 1602b may be referred to herein as systems including a turret 1606a and 1606b, a plurality of workstations 1616, and applicators 1614 with nozzles 1622 for sealant application. Each turret system may be adapted to receive lids from a starwheel (see, e.g., starwheels 2020a and 2020b in FIG. 20) which is adapted to receive the lids from a downstacker (e.g., downstackers 1604a and 1604b). The turret systems 1602a and 1602b may be installed at the top of a table or platform surface 1618a and 1618b and rotate in opposition directions from one another (as depicted by the arrows). In the illustrated embodiment, the tables or platform surfaces 1618a and 1618b are separate to enable the turret systems 1602a and 1602b to be separately maintained or repaired such that if one of the turret systems requires maintenance or breaks down, the other turret system can continue to operate, increasing production time and increasing profits. The turret systems 1602a and 1602b each include a plurality of workstations 1616 which extend out from each turret system facing away from each other.

The workstations 1616 receive an individual lid from a downstacker. In the dual turret system 1600, there are two downstackers 1604a and 1604b, each downstacker connected to each turret system 1602a and 1602b. The starwheels 2020a and 2020b adapted to deliver lids from each downstacker to each turret are rotatable in an opposite direction from its respective turret, and in an opposite direction from the other starwheel 2020b or 2020a. Sealant injectors or applications 1614 may be installed in the workstations to apply sealant to each metal lid as the lids rotate around each turret 1606a and 1606b.

As shown in FIG. 16, a rod cage 1610a and 1610b is attached to each downstacker 1604a and 1604b. In some implementations, a rod cage 1610a and 1610b may not be used and a belt (not shown) or conveyor (not shown) feeds can ends directly into the machine.

When applying sealant to a can end or container closure member, it may be desirable to closely control the lining time of the can ends. It may be beneficial to maximize the application time of sealant on can ends in order to ensure

comprehensive coverage. In the disclosed technology, the downstackers are located at the outer corner edges of the liner machine system, at approximately $\pm 45^\circ$ from the center axis of the turret **1606a** and **1606b** (as shown in more detail in FIG. 17, depicted with the arrows and axis line), rather than directly opposite the exit chutes (see, e.g., exit chute **1712a** and **1712b** in FIG. 17) on the other side of the table or platform, to allow for additional lining time of the can ends.

FIG. 17 illustrates an example of a turret liner machine system **1700** in accordance with aspects of the present disclosure. Specifically, FIG. 17 is a top view of an asynchronous dual turret liner machine system **1700** for applying a sealing compound to a can end or lid **1790**. The dual turret liner machine **1700** applies a sealant to metal lids, each metal lid being received from a supply conveyor (not shown) and discharged to a discharge conveyor (not shown) via an exit chute **1712a** and **1712b**. The dual turret liner machine **1700** includes two turret systems **1702a** and **1702b** driven by two main drive motors (see, e.g., main drive motors **1640a** and **1640b** in FIG. 16). In some implementations, the liner machine technology may incorporate any number of turrets, drives, motors, chucks, chuck drives, downstackers, and starwheels. The disclosed technology is aimed at performing high speed and high-volume end production with scalable systems.

The turret systems **1702a** and **1702b** may be referred to herein as systems including a turret **1706a** and **1706b**, a plurality of workstations **1716**, and applicators **1714** with nozzles (see, e.g., nozzles **1622** in FIG. 16) for sealant application. Each turret system **1702a** and **1702b** may be adapted to receive lids from a starwheel (see, e.g., starwheels **2020a** and **2020b** in FIG. 20) which is adapted to receive the lids from a downstacker **1704a** and **1704b**. The turret systems **1702a** and **1702b** may be installed at the top of a table or platform surface **1718a** and **1782b** and rotate in opposition directions from one another (as depicted by the arrows). The turret systems **1702a** and **1702b** each include a plurality of workstations **1716** which extend out from each turret system facing away from each other.

The workstations **1716** receive an individual lid (not shown) from a downstacker **1704a** and **1704b**. In the dual turret system **1700**, there are two downstackers **1704a** and **1704b**, each downstacker **1704a** and **1704b** connected to each turret system **1702a** and **1702b**. The starwheels **2020a** and **2020b** adapted to deliver lids from each downstacker to each turret **1706a** and **1706b** are rotatable in an opposite direction from its respective turret **1706a** and **1706b**, and in an opposite direction from the other starwheel **2020b** or **2020a**. Sealant injectors or applications **1714** may be installed in the workstations **1716** to apply sealant to each metal lid as the lids rotate around each turret.

When applying sealant to a can end or container closure member, it may be desirable to closely control the lining time of the can ends. It may be beneficial to maximize the application time of sealant on can ends in order to ensure comprehensive coverage. In the disclosed technology, the downstackers **1704a** and **1704b** are located at the outer corner edges of the liner machine system, at approximately $\pm 45^\circ$ from the center axis of the turret (as depicted with the arrows and axis line), rather than directly opposite the exit chutes **1712a** and **1712b** on the other side of the table or platform, to allow for additional lining time of the can ends.

FIG. 18 illustrates an example of a turret liner machine system **1800** in accordance with aspects of the present disclosure. Specifically, FIG. 18 is a side view of an asynchronous dual turret liner machine system **1800** for apply-

ing a sealing compound to a can end or lid **1790** (shown in FIG. 17). The dual turret liner machine **1800** applies a sealant to metal lids, each metal lid being received from a supply conveyor (not shown) and discharged to a discharge conveyor (not shown) via an exit chute (see, e.g., exit chute **1712a** and **1712b** in FIG. 17). The dual turret liner machine **1800** includes two turret systems **1802a** and **1802b** driven by two main drive motors **1840a** and **1840b**. In some implementations, the liner machine technology may incorporate any number of turrets, drives, motors, chucks, chuck drives, downstackers, and starwheels. The disclosed technology is aimed at performing high speed and high-volume end production with scalable systems.

The turret systems **1802a** and **1802b** may be referred to herein as systems including a turret **1806a** and **1806b**, a plurality of workstations **1816**, and applicators **1814** with nozzles **1822** for sealant application. Each turret system **1802a** and **1802b** may be adapted to receive lids from a starwheel (see, e.g., starwheels **2020a** and **2020b** in FIG. 20) which is adapted to receive the lids from a downstacker **1804a** and **1804b**. The turret systems **1802a** and **1802b** may be installed at the top of a table or platform surface **1818a** and **1818b** and rotate in opposition directions from one another (as depicted by the arrows). The turret systems **1802a** and **1802b** each include a plurality of workstations **1816** which extend out from each turret system facing away from each other.

The workstations **1816** receive an individual lid from a downstacker **1804a** and **1804b**. In the dual turret system **1800**, there are two downstackers **1804a** and **1804b**, each downstacker **1804a** and **1804b** connected to each turret system **1802a** and **1802b**. The starwheels **2020a** or **2020b** adapted to deliver lids from each downstacker **1804a** and **1804b** to each turret **1806a** and **1806b** are rotatable in an opposite direction from its respective turret **1806a** and **1806b**, and in an opposite direction from the other starwheel **2020b** or **2020a**. Sealant injectors or applications **1814** may be installed in the workstations **1816** to apply sealant to each metal lid as the lids rotate around each turret **1806a** and **1806b**.

When applying sealant to a can end or container closure member, it may be desirable to closely control the lining time of the can ends. It may be beneficial to maximize the application time of sealant on can ends in order to ensure comprehensive coverage. In the disclosed technology, the downstackers **1804a** and **1804b** are located at the outer corner edges of the liner machine system, at approximately $\pm 45^\circ$ from the center axis of the turret, rather than directly opposite the exit chutes on the other side of the table or platform **1818a** and **1818b**, to allow for additional lining time of the can ends.

When a lid or can end leaves a starwheel **2020a** or **2020b**, the can end is in a down position. The starwheel **2020a** or **2020b** rotates the lid around to meet a lower chuck **1824**. Specifically, each turret **1806a** and **1806b** includes a plurality of lower chucks **1824** each configured to receive a lid, rotate the lid around the turret **1806a** and **1806b** and rotate the lid as the sealing compound is applied to the lid. The lower chucks **1824** pick up the lid, and a lift cam **1826a** and **1826b** lifts the lower chuck **1824** to a workstation **1816** on the turret system **1802a** and **1802b**. The lift cam **1824** includes a cam ring **1850** and each lower chuck **1824** includes a plurality of wheels **1852** attached to each lower chuck **1824** and configured to interface with the cam ring **1850**. The cam ring **1850** is sized and shaped to raise each lower chuck **1824** when the lower chuck **1824** receives a lid such that the lid is positioned proximate a nozzle **1822** to

receive sealing compound. Additionally, the cam ring 1850 is sized and shaped to lower each lower chuck 1824 when the lower chuck 1824 unloads a lid to an exit chute (see, e.g., exit chute 1712a and 1712b in FIG. 17). In the illustrated embodiment, the cam ring 1850 includes a race (not shown) that has a variable height relative to the table or platform surface 1818a and 1818b. The wheels 1852 roll on the race and change the height of the lower chucks 1824 as the lower chucks 1824 rotate around the turret 1806a and 1806b.

When the lift cam 1826 is in the up position, rising above the platform 1818a and 1818b to the applicator 1814, the lid is rotated approximately 150° in the upright position, as the sealant is applied to the lid. In the disclosed technology, as a result of the locations of each downstacker, each lift cam 1826 is longer. The longer length of the lift cam 1826 allows for the lid or can end to be on the lift cam 1826 longer, thus, allowing for more sealant application time. In other liner machine technology, lift cams are approximately 125° in duration (of a 360° rotation) in the upright position (not accounting for the up ramp and down ramp distance). In the disclosed technology, the lift cams 1826 are approximately 150° degrees because of the distance from a downstacker 1804a and 1804b to the exit chute 1712a and 1712b.

Moreover, the longer length of the lift cam 1826 enables the turret systems 1802a and 1802b to rotate at a higher rate. Specifically, some can end machines only rotate at 150 rotations per minute (rpm). In contrast, the longer length of the lift cam 1826 enables the turret systems 1802a and 1802b described herein to rotate at 250 rpm, enabling the turret systems 1802a and 1802b to process more can ends or lids 1790. Additionally, the longer length of the lift cam 1826 also enables the lid or can end 1790 to be rotated about the lower chuck 1824 three times as the lid or can end 1790 is rotated about the lift cam 1826. Rotating the lid or can end 1790 three times about the lower chuck 1824 also enables more sealant to be applied to the lid or can end 1790. In contrast, at least some known can end machines only rotate the can end or lid once or twice. Thus, the longer length of the lift cam 1826 enables more sealant to be applied to the can end or lid 1790 and enables the turret systems 1802a and 1802b to process more can ends or lids 1790.

FIG. 19 illustrates an example of a turret liner machine system 1900 in accordance with aspects of the present disclosure. Specifically, FIG. 19 is a bottom view of an asynchronized dual turret liner machine system 1900 for applying a sealing compound (not shown) to a can end or lid 1790 (shown in FIG. 17). The dual turret liner machine 1900 applies a sealant to metal lids, each metal lid being received from a supply conveyor (not shown) and discharged to a discharge conveyor (not shown) via an exit chute 1912a and 1912b. The dual turret liner machine 1900 includes two turret systems 1902a and 1902b driven by two main drive motors 1940a and 1940b. In some implementations, the liner machine technology may incorporate any number of turrets, drives, motors, chucks, chuck drives, downstackers, and starwheels. The disclosed technology is aimed at performing high speed and high-volume end production with scalable systems.

The turret systems 1902a and 1902b may be referred to herein as systems including a turret 1906a and 1906b, a plurality of workstations (see, e.g., workstations 1616, 1716, and 1816 in FIGS. 16-18), and applicators (see, e.g., applicators 1614, 1714, and 1814 in FIGS. 16-18) with nozzles (see, e.g., applicators 1622, 1722, and 1822 in FIGS. 16-18) for sealant application. Each turret system 1902a and 1902b may be adapted to receive lids from a starwheel (see, e.g., starwheels 2020a and 2020b in FIG. 20) which is adapted to

receive the lids from a downstacker (e.g., downstackers 1904a and 1904b). The turret systems 1902a and 1902b may be installed at the top of a table or platform surface 1918a and 1918b and rotate in opposition directions from one another (as depicted by the arrows). The turret systems 1902a and 1902b each include a plurality of workstations (see, e.g., workstations 1616, 1716, and 1816 in FIGS. 16-18) which extend out from each turret system facing away from each other.

10 The workstations receive an individual lid from a downstacker 1904a and 1904b. In the dual turret system 1900, there are two downstackers 1904a and 1904b, each downstacker 1904a and 1904b connected to each turret system 1902a and 1902b. The starwheels 2020a and 2020b adapted to deliver lids from each downstacker 1904a and 1904b to each turret are rotatable in an opposite direction from its respective turret, and in an opposite direction from the other starwheel 2020b or 2020a. Sealant injectors or applications may be installed in the workstations to apply sealant to each

20 metal lid as the lids rotate around each turret.

When applying sealant to a can end or container closure member, it may be desirable to closely control the lining time of the can ends. It may be beneficial to maximize the application time of sealant on can ends in order to ensure comprehensive coverage. In the disclosed technology, the downstackers 1904a and 1904b are located at the outer corner edges of the liner machine system, at approximately ±45° from the center axis of the turret, rather than directly opposite the exit chutes on the other side of the table or

30 platform, to allow for additional lining time of the can ends.

The turrets 1906a and 1906b each include a turret gear 1930a and 1930b, the main drive motors 1940a and 1940b each include a main drive gear 1932a and 1932b, the starwheels 2020a or 2020b each include a starwheel gear 1936a and 1936b, and the lower chucks 1824 each include a lower chuck gear 1938a and 1938b. The turret gears 1930a and 1930b are configured to rotate the turrets 1906a and 1906b, the starwheel gears 1936a and 1936b are configured to rotate the starwheels 2020a or 2020b, and the lower chuck gears 1938a and 1938b are configured to rotate the lower chucks 1824. In the illustrated embodiment, the main drive gears 1932a and 1932b are rotatably coupled to the turret gears 1930a and 1930b respectively. The turret gears 1930a and 1930b are rotatably coupled to the starwheel gear 1936a and 1936b respectively. In the illustrated embodiment, the lower chuck gear 1938a and 1938b are independently driven by a chuck gear motor (not shown). In alternative embodiments, the lower chuck gear 1938a and 1938b may be driven by the turret gears 1930a and 1930b, the starwheel gears 1936a and 1936b, and/or the main drive gears 1932a and 1932b.

During operations, the main drive motors 1940a and 1940b rotate the 1932a and 1932b which rotate the turret gears 1930a and 1930b respectively. The turret gears 1930a and 1930b rotate the turrets 1906a and 1906b and the starwheel gears 1936a and 1936b respectfully. The starwheel gears 1936a and 1936b rotate the starwheels 2020a and 2020b. Accordingly, in the illustrated embodiment, the turret gears 1930a and 1930b, the main drive gear 1932a and 1932b, the starwheel gears 1936a and 1936b, and the lower chuck gears 1938a and 1938b are arranged to drive both turret systems 1902a and 1902b with two main drive motors 1940a and 1940b, increasing production time, increasing profits, and reducing the overall footprint of the turret liner machine system 1900.

FIG. 20 illustrates an example of a turret liner machine system 2000 in accordance with aspects of the present

disclosure. Specifically, FIG. 20 is a top view of an asynchronous dual turret liner machine system 2000 for applying a sealing compound to a can end or lid 1790 (shown in FIG. 17). The dual turret liner machine 2000 applies a sealant to metal lids, each metal lid being received from a supply conveyor (not shown) and discharged to a discharge conveyor (not shown) via an exit chute 2012. The dual turret liner machine 2000 includes two turret systems 2002a and 2002b driven by two main drive motors (see, e.g., main drive motor 1940a and 1940b in FIG. 19). In some implementations, the liner machine technology may incorporate any number of turrets, drives, motors, chucks, chuck drives, downstackers, and starwheels. The disclosed technology is aimed at performing high speed and high-volume end production with scalable systems.

The turret systems 2002a and 2002b may be referred to herein as systems including a turret 2006a and 2006b, a plurality of workstations 2016, and applicators 2014 with nozzles (see, e.g., nozzles 1622 in FIG. 16) for sealant application. Each turret system 2002a and 2002b may be adapted to receive lids from a starwheel 2020a and 2020b which is adapted to receive the lids from a downstacker 2004a and 2004b). The turret systems 2002a and 2002b may be installed at the top of a table or platform surface 2018a and 2018b and rotate in opposition directions from one another (as depicted by the arrows). The turret systems 2002a and 2002b each include a plurality of workstations 2016 which extend out from each turret system facing away from each other.

The workstations 2016 receive an individual lid (not shown) from a downstacker 2004a and 2004b. In the dual turret system 2000, there are two downstackers 2004a and 2004b, each downstacker 2004a and 2004b connected to each turret system 2002a and 2002b. The starwheels 2020a and 2020b adapted to deliver lids from each downstacker to each turret 2006a and 2006b is rotatable in an opposite direction from its respective turret 2006a and 2006b, and in an opposite direction from the other starwheel 2020b or 2020a. Sealant injectors or applications 2014 may be installed in the workstations 2016 to apply sealant to each metal lid as the lids rotate around each turret.

When applying sealant to a can end or container closure member, it may be desirable to closely control the lining time of the can ends. It may be beneficial to maximize the application time of sealant on can ends in order to ensure comprehensive coverage. In the disclosed technology, the downstackers 2004a and 2004b are located at the outer corner edges of the liner machine system, at approximately $\pm 45^\circ$ from the center axis of the turret (as depicted with the arrows and axis line), rather than directly opposite the exit chutes 2012a and 2012b on the other side of the table or platform, to allow for additional lining time of the can ends.

FIG. 21 illustrates an example of a turret liner machine system 2100 in accordance with aspects of the present disclosure. Specifically, FIG. 21 is a perspective view of dual turret liner machine systems 100-2000 for applying a sealing compound to a can end or lid 490, 790, 1290, and 1790 and the turret liner machine system 2100 is illustrative of a super structure 2160 of dual turret liner machine systems 100-2000. The turret liner machine 2100 applies a sealant (not shown) to metal lids, each metal lid being received from a supply conveyor (not shown) and discharged to a discharge conveyor (not shown) via an exit chute (see, e.g., exit chute 2112a and 2112b). In the illustrated embodiment, the dual turret liner machine 2100 includes two turret systems 2102a and 2102b driven by two main drive motors (not shown) or a single main drive motors

(not shown) as described above. The main drive motor(s) are located proximate to the respective turret systems and may be configured to operate both turret systems 2102a and 2102b, increasing production time and increasing profits. In some implementations, the liner machine technology may incorporate any number of turrets, drives, motors, chucks, chuck drives, downstackers, and starwheels. The disclosed technology is aimed at performing high speed and high-volume end production with scalable systems.

The super structure 2160 includes a frame 2162, paneling 2164 attached to the frame 2162, a tank system 2166a and 2166b attached to each turret system 2102a and 2102b, and at least one door 2168 attached to the frame 2162. The super structure 2160 is attached to a table or platform surface 2118a and 2118b and is configured to support the tank systems 2166a and 2166b and protect operators and the turret systems 2102a and 2102b during use. Specifically, as described above, the turret systems 2102a and 2102b are configured to rotate at a high rate (i.e., 3,000 rpm) and the super structure 2160 is configured to prevent operators and/or other objects from interfering with that rotation. More specifically, the paneling 2164 and the door 2168 are configured to protect the turret systems 2102a and 2102b and the operators by preventing operators and/or other objects from interfering with rotation of the turret systems 2102a and 2102b. In the illustrated embodiment, the super structure 2160 includes four doors 2168a, 2168b, 2268c (shown in FIG. 22), and 2268d (shown in FIG. 22). The doors 2168 are configured to enable selective access to the turret systems 2102a and 2102b when the turret systems 2102a and 2102b are not operating.

The tank systems 2166a and 2166b each include a tank 2170a and 2170b and an attachment mechanism 2172a and 2172b attached to the tank 2170a and 2170b. The tanks 2170a and 2170b are each configured to contain a sealant solution that is applied to the can lids 490, 790, 1290, and 1790 by the turret systems 2102a and 2102b. Specifically, the tanks 2170a and 2170b are configured to channel the sealant solution to the nozzles 122-2022 described above for application to the can lids 490, 790, 1290, and 1790. The tanks 2170a and 2170b are each configured to rotate with their respective turret systems 2102a and 2102b, and the attachment mechanisms 2172a and 2172b are configured to attach the tanks 2170a and 2170b to the frame 2162 to structurally support the tanks 2170a and 2170b. The attachment mechanisms 2172a and 2172b remain stationary and are configured to support the tanks 2170a and 2170b as the tanks 2170a and 2170b rotate.

The turret liner machine system 2100 further includes a shell 2174, a skirt 2176, and a control panel 2178. The shell 2174 is attached to and extends below the table or platform surface 2118a and 2118b and is configured to protect the internal components of the turret liner machine system 2100. The skirt 2176 is attached to the shell 2174, extends below the shell 2174, and is also configured to protect the internal components of the turret liner machine system 2100. The skirt 2176 defines a plurality of holes 2180 that enable air to flow to the internal components of the turret liner machine system 2100 and enable the internal components to be air cooled. The control panel 2178 is attached to the shell 2174 and enables an operator to operate the turret liner machine system 2100.

FIG. 22 illustrates an example of a turret liner machine system 2200 in accordance with aspects of the present disclosure. Specifically, FIG. 22 is a perspective view of dual turret liner machine systems 100-2000 for applying a sealing compound to a can end or lid 490, 790, 1290, and

1790 and the turret liner machine system 2200 is illustrative of a super structure 2260 of dual turret liner machine systems 100-2000. The turret liner machine 2200 applies a sealant (not shown) to metal lids, each metal lid being received from a supply conveyor (not shown) and discharged to a discharge conveyor (not shown) via an exit chute (see, e.g., exit chute 2112a and 2112b shown in FIG. 21). In the illustrated embodiment, the dual turret liner machine 2200 includes two turret systems 2202a and 2202b driven by two main drive motors (not shown) or a single main drive motors (not shown) as described above. The main drive motor(s) are located proximate to the respective turret systems and may be configured to operate both turret systems 2202a and 2202b, increasing production time and increasing profits. In some implementations, the liner machine technology may incorporate any number of turrets, drives, motors, chucks, chuck drives, downstackers, and starwheels. The disclosed technology is aimed at performing high speed and high-volume end production with scalable systems.

The super structure 2260 includes a frame 2262, paneling 2264 attached to the frame 2262, a tank system 2266a and 2266b attached to each turret system 2202a and 2202b, and at least one door 2268 attached to the frame 2262. The super structure 2260 is attached to a table or platform surface 2218a and 2218b and is configured to support the tank systems 2266a and 2266b and protect operators and the turret systems 2202a and 2202b during use. Specifically, as described above, the turret systems 2202a and 2202b are configured to rotate at a high rate (i.e., 3,000 rpm) and the super structure 2260 is configured to prevent operators and/or other objects from interfering with that rotation. More specifically, the paneling 2264 and the door 2268 are configured to protect the turret systems 2202a and 2202b and the operators by preventing operators and/or other objects from interfering with rotation of the turret systems 2202a and 2202b. In the illustrated embodiment, the super structure 2260 includes four doors 2168a, 2168b, 2268c (shown in FIG. 22), and 2268d (shown in FIG. 22). The doors 2268 are configured to enable selective access to the turret systems 2202a and 2202b when the turret systems 2202a and 2202b are not operating.

The tank systems 2266a and 2266b each include a tank 2270a and 2270b and an attachment mechanism 2272a and 2272b attached to the tank 2270a and 2270b. The tanks 2270a and 2270b are each configured to contain a sealant solution that is applied to the can lids 490, 790, 1290, and 1790 by the turret systems 2202a and 2202b. Specifically, the tanks 2270a and 2270b are configured to channel the sealant solution to the nozzles 122-2022 described above for application to the can lids 490, 790, 1290, and 1790. The tanks 2270a and 2270b are each configured to rotate with their respective turret systems 2202a and 2202b, and the attachment mechanisms 2272a and 2272b are configured to attach the tanks 2270a and 2270b to the frame 2262 to structurally support the tanks 2270a and 2270b. The attachment mechanisms 2272a and 2272b remain stationary and are configured to support the tanks 2270a and 2270b as the tanks 2270a and 2270b rotate.

The turret liner machine system 2200 further includes a shell 2274, a skirt 2276, and a control panel 2278. The shell 2274 is attached to and extends below the table or platform surface 2218a and 2218b and is configured to protect the internal components of the turret liner machine system 2200. The skirt 2276 is attached to the shell 2274, extends below the shell 2274, and is also configured to protect the internal components of the turret liner machine system 2200. The

skirt 2276 defines a plurality of holes 2280 that enable air to flow to the internal components of the turret liner machine system 2200 and enable the internal components to be air cooled. The control panel 2278 is attached to the shell 2274 and enables an operator to operate the turret liner machine system 2200. FIG. 23 shows a flowchart of operations 2300 that support a dual turret liner machine system in accordance with aspects of the present disclosure. In some implementations, there may be one or three or more turrets in the liner machine system. In the implementation described in operations 2300, the dual turret system may be supported by one main drive. In other implementations supporting more turrets, it is contemplated that more than one main drive will be required. The turret liner machine systems disclosed herein are scalable.

An operation 2302 drives a first turret system in a first direction. An operation 2304 drives a second turret system in a second direction. The second turret system may rotate in a direction that is opposite from the direction of the first turret system. They are counter-rotating to each other.

An operation 2306 receives a first plurality of lids from a first infeed conveyor connected to a first downstacker via a first starwheel into the first turret system. The first starwheel may be rotating in a direction opposite to the direction of the rotation of the first turret system. Similarly, an operation 2308 receives a second plurality of lids from a second infeed conveyor connected to a second downstacker via a second starwheel into the second turret system. The second starwheel may be rotating in a direction opposite to the direction of the rotation of the second turret system. In some implementations, the first starwheel may rotate in a direction that is opposite to the second starwheel.

An operation 2310 applies sealant to the first plurality of lids and the second plurality of lids. In some implementations, sealant is applied at individual workstations located in the first turret system and in the second turret system via nozzles of applicators or sealing guns.

An operation 2312 discharges the first plurality of lids and the second plurality of lids with sealant thereon to a first discharge conveyor, and a second discharge conveyor, respectively.

In some implementations, the liner machine system includes at least one lower chuck drive. For example, there may be a first lower chuck drive connected to the first turret system and a second lower chuck drive connected to the second turret system. The first lower chuck drive may rotate in a direction that is opposite from the direction that the second lower chuck drive rotates.

It should be noted that these methods describe examples of implementations, and that the operations and the steps may be rearranged or otherwise modified such that other implementations are possible. In some examples, aspects from two or more of the methods may be combined. For example, aspects of each of the methods may include steps or aspects of the other methods, or other steps or techniques described herein. Thus, aspects of the disclosure may provide for consumer preference and maintenance interface.

The description set forth herein, in connection with the appended drawings, describes example configurations and does not represent all the examples that may be implemented or that are within the scope of the claims. The term "exemplary" used herein means "serving as an example, instance, or illustration," and not "preferred" or "advantageous over other examples." The detailed description includes specific details for the purpose of providing an understanding of the described techniques. These techniques, however, may be

33

practiced without these specific details. In the appended figures, similar components or features may have the same reference label.

The description herein is provided to enable a person skilled in the art to make or use the disclosure. Various modifications to the disclosure will be readily apparent to those skilled in the art, and the generic principles defined herein may be applied to other variations without departing from the scope of the disclosure. Thus, the disclosure is not limited to the examples and designs described herein but is to be accorded the broadest scope consistent with the principles and novel features disclosed herein.

What is claimed is:

1. A sealant liner apparatus comprising:
two motor driven turret systems, including a first turret system that rotates in a direction that is opposite a direction that a second turret system rotates;
two main drive motors to drive each of the two motor driven turret systems, wherein a first main drive motor is configured to drive the first turret system and a second main drive motor is configured to drive the second turret system;
a plurality of workstations located on each of the two motor driven turret systems spaced apart and extending outwardly from a circumference thereof, each workstation of the plurality of workstations adapted for receiving an individual can end;
two downstackers, each downstacker of the two downstackers located proximate to a turret system of the two motor driven turret systems to feed the individual can end to an individual workstation of the plurality of workstations and proximate to an exit chute that discharges the individual can end from the turret system of the two motor driven turret systems; and
at least one sealant applicator mounted on each individual workstation of the plurality of workstations, the at least one sealant applicator electronically controlled to apply a sealant on the individual can end, wherein the exit chute comprises a first exit chute and the sealant liner apparatus further comprises a second exit chute, the first turret system configured to discharge the individual can end to the first exit chute and the second turret system configured to discharge the individual can end to the second exit chute, and wherein the first exit chute and the second exit chute are both positioned on a first side of the sealant liner apparatus and discharge the individual can end to the first side of the sealant liner apparatus to a single discharge conveyor.

vidual can end to the first exit chute and the second turret system configured to discharge the individual can end to the second exit chute, and wherein the first exit chute and the second exit chute are both positioned on a first side of the sealant liner apparatus and discharge the individual can end to the first side of the sealant liner apparatus to a single discharge conveyor.

2. The sealant liner apparatus of claim 1, wherein a starwheel adapted to receive the individual can end and feed the individual can end to a respective turret system of the two motor driven turret systems rotates in a direction that is opposite a direction that the respective turret system of the two motor driven turret systems rotates.

3. The sealant liner apparatus of claim 1, wherein a first starwheel rotates in a direction that is opposite a direction of a second starwheel.

4. The sealant liner apparatus of claim 1, wherein each downstacker of the two downstackers is located approximately +45° from a center axis of each turret system of the two motor driven turret systems.

5. The sealant liner apparatus of claim 1, further comprising:

a lift cam, wherein a length of the lift cam is approximately 150°.

6. The sealant liner apparatus of claim 5, wherein a first downstacker of the two downstackers is located proximate to the first exit chute, and the individual can end rotates around a turret system of the two motor driven turret systems in a clockwise direction.

7. The sealant liner apparatus of claim 5, wherein a second downstacker of the two downstackers is located proximate to the second exit chute, and the individual can end rotates around a turret system of the two motor driven turret systems in a counterclockwise direction.

8. The sealant liner apparatus of claim 1, further comprising:

two lower chuck drives, each lower chuck drive of the two lower chuck drives configured to each rotate in a direction that is opposite a direction that the other lower chuck drive of the two lower chuck drives rotates.
